UNITED STATES PATENT OFFICE.

WILLIAM R. BAKER, OF CHICAGO, ILLINOIS, ASSIGNOR TO C. H. AND L. J. McCORMICK, OF SAME PLACE.

IMPROVEMENT IN GRAIN-BINDERS.

Specification forming part of Letters Patent No. 171,972, dated January 11, 1876; application filed November 12, 1875.

To all whom it may concern:

Be it known that I, WILLIAM R. BAKER, of Chicago, in the county of Cook and State of Illinois, have invented a new and useful Improvement in Twister-Wheels for Automatic Grain-Binders, of which the following is a specification:

My invention constitutes an improvement on the well-known "Withington Grain-Binder," built by C. H. and L. J. McCormick, of Chicago, Illinois, in which the cutting or twisting device consists of two symmetrical pinions revolving around a common axis, working together to twist the wire, but having a differential movement to cut the same.

The object of my invention is to secure the steady working of the pinions. To this end my improvement consists in constructing the twister of two pinions revolving close together around a common axis, with an annular groove at their point of contact with each other, in which groove fits a fixed plate forming part of the binding-head, and constituting a bearing for the points of the teeth of the pinions, and leaving a space between the inner edge of the plate and the center of the pinions, through which the wires travel during the operation of twisting.

In the accompanying drawings, Figure 1 represents a plan view of a portion of the mechanism of the well-known Withington binder; Fig. 2, a plan view of the twister-pinions and their interposed plate, the face-plate of the binding-head being removed; Fig. 3, a vertical section through the binder-head on the line *xx* of Fig. 1.

The binding mechanism herein shown is fully described in an application for Letters Patent of the United States, filed March 5,

1874, by Charles B. Withington, and also in an application for Letters Patent for a fixed stop in connection therewith, by Robert Hall McCormick, filed simultaneously herewith; and as my invention relates to the twister-pinions and their supporting-plate, I shall confine my description to those features.

The pinions *A A'* are shown as mounted on a common pivot, *a*, with their teeth deeply indented. The pinions are capable of turning either together or independently of each other, but work in close contact, except on their peripheries, where an annular groove, *c*, is formed at their point of junction for the reception of a plate, *C*, firmly secured in a binding-head, and slotted in conformity therewith to permit of the passage of the wire to the pinions. The points of the teeth of the pinions work in slots or spaces between the upper and lower covers of the binding-head and this plate, which plate forms a bearing for the pinion, thus affording a support at that point, while a space is left between the center of the pinion and the inner edges of these inclosing-plates through which the wire passes while being twisted. The covering-plates keep out dirt, &c., and serve as guides for the wire in entering the twister.

I claim as of my invention—

The combination of the twister-pinions and their fixed supporting-plate inserted in an annular groove therein, substantially as hereinbefore set forth.

In testimony whereof I have hereunto subscribed my name.

WM. R. BAKER.
